CORE CATCHER

Carl Francis Baker, Taft, Calif.

Application April 25, 1936, Serial No. 76,476
Renewed December 30, 1938

5 Claims. (Cl. 255—73)

This invention relates to well drilling apparatus, and particularly pertains to a core barrel and catcher adapted to be used in conjunction with a conventional type of core drill.

5 In obtaining samples of formation from oil wells it is common practice to drill ahead of the normal drilled depth of the well to cut a cylindrical solid core. These cores are removed from the well after having been cut by a circular cutter having a central opening to accommodate the core, and when removed give geological information relative to the formation which would be penetrated if the well bore is to continue to a greater depth. Various devices 10 have been provided to catch the cut core and to insure that when the core drill is removed from the well the sample would be properly extracted. These structures have in a great many instances been complicated and do not 15 always operate positively. It is the principal object of the present invention therefor to provide a core catcher which may be positively drilled from the top of the well and which will act to engage the core and insure that it is extracted when the core catcher is withdrawn.

20 The present invention contemplates the provision of a tubular member within which a core may be caught, said member having means associated therewith for engaging the core at its lower end and holding the same while it is extracted, the operation of the device being effected by imposing fluid pressure upon the core catcher from the top of the well to actuate the core engaging elements and to hold them in 25 actuated position until the core is recovered.

30 35 The invention is illustrated by way of example in the accompanying drawing in which:

Figure 1 is a view in elevation showing the present invention as attached to a drill pipe with parts thereof broken away for the sake of convenience.

40 Fig. 2 is an enlarged view in longitudinal section showing the core catching device in its inoperative position.

45 Fig. 3 is an enlarged view in vertical section similar to Fig. 2 and showing the core catcher in its operative position.

Fig. 4 is a view in transverse section through the core catcher as seen on the line 4—4 of Fig. 2.

50 Fig. 5 is a view in transverse section through the core catcher as seen on the line 5—5 of Fig. 2.

Fig. 6 is a view in transverse section through the core catcher as seen on the line 6—6 of Fig. 3 and shows the core engaging elements in their set position.

55 Referring more particularly to the drawing, 10 indicates a drill stem at the lower end of which a core catcher 11 is secured, and beneath which

a core drill bit 12 is attached. The bit 12 may be of any desired construction to cut a cylindrical core from formation being penetrated. At the upper end of the drill string is a fitting 13 carrying a valve 14 through which a valve ball may 5 be introduced into the drill string and allowed to drop to the bottom of the well in a manner to be hereinafter described. The valve structure includes a rotatable valve 15 having an opening 16 therein through which the valve may 10 pass and after which the valve may be closed to permit fluid pressure to be imposed upon a column of fluid within the drill string. It will be understood that suitable connections are provided at the upper end of the fitting 13 to establish 15 communication with the drilling fluid circulating pumps at the well and for the purpose of forcing fluid downwardly within the drill string to actuate the core catcher in a manner to be hereinafter described.

20 The core catcher comprises an outer housing 17, the upper end of which receives the lower threaded end of the drill string 10. This housing has a central cylindrical bore 18 therethrough continuing in an outwardly tapering bore 19 and an enlarged cylindrical bore 20. The lower 25 end of the housing is threaded at 21 to receive a bottom closure structure 22 carrying a threaded sub 23 adapted to engage a tubular member 24 by which the core drill bit 12 is supported. The portion of the structure 22 above the sub 23 comprises a cylindrical wall 25 substantially the same diameter as the lower wall section 26 of the housing 17 and an end wall 27. Fluid 30 circulating openings 28 are formed through the end wall 27 to make it possible for the drilling fluid 35 of the well to circulate downwardly and outwardly into the well bore and thereafter upwardly to the top of the well in the usual manner. The sub or threaded pin 23 is formed with a central passageway 29 therethrough to accommodate the 40 upwardly projecting end of the core being cut and to permit this core to pass upwardly into the core barrel and catcher as core drilling progresses. Mounted in the end wall 27 of the structure 22 is a core guide sleeve 30 which has a central passageway 31 through it in longitudinal alignment with the central passageway 29 through the pin 23. The core guide sleeve structure 30 includes a threaded base portion 32 adapted to be screwed into a threaded counterbore 33 provided in the end wall 27 of the sub 23 and above which a cylindrical portion 34 occurs having side passageways 35 therethrough to receive core cutting and retaining dogs 36 operating 45 in a manner to be hereinafter described. Above the cylindrical portion 34 is a reduced cylindrical portion 37 through which the upper end of the passageway 31 occurs. The reduced cylindrical portion of the guide sleeve extends through a 50

55

60

cross head 38 which, as shown in Fig. 5, comprises a central circular portion 39 and radial arms 40. The radial arms 40 extend outwardly and terminate in arcuate end faces which 5 form to the inner circumference of the wall portion 26 of the main housing 17. Threaded into the wall 26 at diametrically opposite sides thereof are shear pins 41 having extensions 42 project into recesses formed in the ends of the 10 radial arms 40 of the cross head 38. These pins temporarily hold the cross head 38 in an inoperative and immovable position with relation to the housing structure 17. An inner core barrel 43 at its lower end is threaded into the central 15 bore 44 of the cross head 38. The core guide sleeve extends into the lower end of the inner core barrel 43 and has a sliding fit with relation thereto so that the inner core barrel may move downwardly over the upwardly extending core 20 guide sleeve. The upper end of the inner core barrel 43 is fitted with a valve ball seat 45 upon which a valve ball 46 rests. A perforated valve cage 47 is detachably mounted on the upper end of the core barrel 43 and above the valve 25 seat 45 so that the valve ball 46 will be retained in the valve cage 47, and so that fluid may flow through the perforations in the cage when the valve ball is unseated. The top of the valve cage terminates at a point slightly below a fluid 30 inlet tube 48 which is fitted with packing rings 49 by which a tight fit occurs between the tube 48 and the wall of the central bore 18 occurring within the upper end of the housing 17. The upper end of tube 48 is fitted with a nut 50 35 threaded thereon to hold the packing rings 49 in position. The nut 50 has a central tapered opening leading downwardly and inwardly to form a seat for a valve ball 51 which may be dropped into the drill pipe through the valve 14 40 previously described.

Extending downwardly from the inlet tube 48 and telescoping over the inner core barrel 43 is an operating sleeve 52. The wall of sleeve 52 flares outwardly toward its lower end and rests against 45 the upper face of the cross head 38. The diameter of the lower open end of the operating sleeve 52 is materially greater than the diameter of the hub 39 of the cross head 38, so that fluid passageways 53 will occur around the cross head and permit the 50 drilling fluid to flow outwardly through the passageways 28 in the bottom closure structure 22. Downward movement of the operating sleeve 50 is produced by the pressure of fluid forced downwardly through the drill pipe 10 and encountering 55 the valve ball 51 after it has been dropped upon its seat. Mounted upon the under face of the cross head 38 are the core cutting and retaining members 36 which are pivoted thereto on pivot pins 54. The core cutters and retainers 36 are 60 designed to be forced inwardly through openings 35 in the cylindrical portion 34 and to positively impinge against the opposite sides of a core 55.

The free edges of members 36 provide cutters which will act to sever the core and hold the upper 65 cut section of core so as to close the core barrel and to substantially interrupt downward flow of drilling fluid from the barrel.

The under faces of the retainers 36 are serrated as indicated at 56 and engage lock lugs 57 70 which are carried by the member 32 and tend to lock the members 36 in their core retaining positions until the entire structure is removed from a well.

In operation of the present invention the entire 75 core catcher structure is assembled as shown in

Fig. 2 of the drawing, and the cross head 38 is set in its temporarily locked position with the pins 42 holding it against movement. At this time the lower free ends of the core retaining members 36 5 extend into the openings 35 at opposite sides of the member 34. During the cutting of the core a circulation of drilling fluid may be effected in the usual manner by forcing the fluid downwardly through the drill pipe 10 and the tube 48 into the operating sleeve 52, and then around the cross 10 head 38 through the passageways 53, after which the fluid will pass outwardly through the openings 28 into the drill bore. The fluid will then be free to circulate upwardly through the well in the usual manner. When a desired length of core has 15 been cut by the core drill the core catcher may be operated. This is done by first dropping the valve ball 51 through the drill pipe until it rests within the seat at the upper end of the flow tube 48. This will obstruct downward flow of drilling fluid 20 through the flow tube and further force exerted by the drilling fluid will move the tube 48 with its packing downwardly and cause the operating sleeve 52 to force against the cross head 38 and the pins 42 with sufficient pressure to shear the pins 25 42 and to permit the cross head to be released for further downward movement. The downward movement of the cross head will act upon the pivot ends of the members 36 to force the free cutting 30 ends of the members inwardly through the openings 35 and against the sides of the core 55. Rotation of the drill stem and the core catcher structure will act, while the cutting members 36 are urged inwardly to sever the core so that a length 35 will be retained within the core barrel as the members 36 become locked by lugs 57. This will cause the core to be engaged and held. Attention is directed to the fact that as the tube 48 is forced downwardly by the pressure of the fluid acting against the ball 51 the upper end of the nut 40 50 will uncover relief passageways 59 which will allow the downwardly moving drilling fluid to pass out into the drill bore. This will be accompanied by a drop in pressure of the drilling fluid and will indicate to the operator at the top of the well that the core catcher has been actuated to a degree where the members 35 have severed the core and are in a retaining position. Rotation of the device may then be discontinued. As the core retaining elements 36 are forced inwardly their 55 serrations 56 on their outer sides will engage and lock with the lock lugs 57 previously described, and will thus insure that the retaining elements will be held in locked position until the entire structure has been removed from the well. Attention is directed to the fact that as the core moves upwardly within the core barrel 43 during 60 operation of the device, such fluid as occurs within the core barrel 43 may be displaced and will flow out at the upper end of the core barrel by lifting the valve ball 46 and passing through the perforations of the ball cage 47.

It will thus be seen that in the operation of the structure here disclosed a core barrel is provided which will positively sever a core and hold the same as controlled from the top of the well, and that furthermore positive information relative to the operation of the device may be ascertained at the top of the well due to variation in fluid pressure. It will further be evident that the core 70 catcher here disclosed is simple in its construction and operation, and that it may operate positively at all times and without any undue strain.

While I have shown the preferred form of my invention, as now known to me, it will be under- 75

stood that various changes might be made in the combination, construction, and arrangement of parts, by those skilled in the art, without departing from the spirit of the invention as claimed.

5 Having thus described my invention, what I claim and desire to secure by Letters Patent is:

1. In combination with a core drill, a core catcher comprising an outer housing having a connection at its lower end for the core drill 10 and a connection at its upper end for a drill string by which the structure is supported, means being provided to permit the flow of fluid from the drill string through the core catcher and into the well, core retaining means within the housing, a core barrel associated therewith and into which a core may be projected as it is cut, means permitting a circulation of fluid upwardly through the core barrel and preventing a down flow of fluid through the core barrel, a cross head 15 slideable within the housing and carrying the core barrel and core retaining means, an operating tube slideable within the housing and through which a circulation of drilling fluid may normally take place, a valve seat at the upper end of the operating tube and carried thereby, means creating a fluid seal between the bore of the housing and the upper end of said operating tube whereby the flow of fluid around the tube will be prevented, and a valve member adapted to be dropped 20 through the drill string to rest upon the valve seat and prevent circulation of drilling fluid whereby the downward pressure of said fluid will move the operating tube and the cross head to 25 actuate the core retaining means.

2. In combination with a core drill, a core catcher comprising an outer housing having a connection at its lower end for the core drill and a connection at its upper end for a drill string by which the structure is supported, means being provided to permit the flow of fluid from the drill string through the core catcher and into the well, core retaining means within the housing, a core barrel associated therewith and into which a core may be projected as it is cut, means permitting a circulation of fluid upwardly 30 through the core barrel and preventing a down flow of fluid through the core barrel, a cross head slideable within the housing and carrying the core barrel and core retaining means, an operating tube slideable within the housing and through which a circulation of drilling fluid may normally take place, a valve seat at the upper end of the operating tube and carried thereby, means creating a fluid seal between the bore of the housing and the upper end of said operating tube whereby the flow of fluid around the tube will be prevented, a valve member adapted to be dropped 35 through the drill string to rest upon the valve seat and prevent circulation of drilling fluid whereby the downward pressure of said fluid will move the operating tube and the cross head to 40 actuate the core retaining means, and means temporarily holding the cross head against movement until said valve ball has been dropped upon its seat and fluid pressure has been imposed thereon.

3. In combination with a core drill, a core catcher comprising an outer housing having a connection at its lower end for the core drill and a connection at its upper end for a drill string by which the structure is supported, means being provided to permit the flow of fluid from the drill string through the core catcher and into the well, core retaining means within the housing, a core

barrel associated therewith and into which a core may be projected as it is cut, means permitting a circulation of fluid upwardly through the core barrel and preventing a down flow of fluid through the core barrel, a cross head slideable within the housing and carrying the core barrel and core retaining means, an operating tube slideable within the housing and through which a circulation of drilling fluid may normally take place, a valve seat on the upper end of the operating tube and carried thereby, means creating a fluid seal between the bore of the housing and the upper end of said operating tube whereby the flow of fluid around the tube will be prevented, a valve member adapted to be dropped 5 through the drill string to rest upon the valve seat and prevent circulation of drilling fluid whereby the downward pressure of said fluid will move the operating tube and the cross head to 10 actuate the core retaining means, means temporarily holding the cross head against movement until said valve ball has been dropped upon its seat and fluid pressure has been imposed thereon, and means engaging with the core retaining means to temporarily lock them in their grip- 15 positions.

4. In combination with a core drill, a core catcher comprising an outer housing having a connection at its lower end for the core drill and a connection at its upper end for a drill string by which the structure is supported, means being provided to permit the flow of fluid from the drill string through the core catcher and into the well, core retaining means within the housing, a core barrel associated therewith and into which a core may be projected as it is cut, means permitting a circulation of fluid upwardly through the core barrel and preventing a down flow of fluid through the core barrel, a cross head slideable within the housing and carrying the core barrel and core retaining means, an operating tube slideable within the housing and through which a circulation of drilling fluid may normally take place, a valve seat at the upper end of the operating tube and carried thereby, means creating a fluid seal between the bore of the housing and the upper end of said operating tube whereby the flow of fluid around the tube will be prevented, a valve member adapted to be dropped 20 through the drill string to rest upon the valve seat and prevent circulation of drilling fluid whereby the downward pressure of said fluid will move the operating tube and the cross head to 25 actuate the core retaining means, means temporarily holding the cross head against movement until said valve ball has been dropped upon its seat and fluid pressure has been imposed thereon, and means creating a fluid seal between the bore of the housing and the upper end of said operating tube whereby the flow of fluid around the tube will be prevented, a valve member adapted to be dropped 30 through the drill string to rest upon the valve seat and prevent circulation of drilling fluid whereby the downward pressure of said fluid will move the operating tube and the cross head to 35 actuate the core retaining means, means temporarily holding the cross head against movement until said valve ball has been dropped upon its seat and fluid pressure has been imposed thereon, and means creating a fluid seal between the bore of the housing and the upper end of said operating tube whereby the flow of fluid around the tube will be prevented, a valve member adapted to be dropped 40 through the drill string to rest upon the valve seat and prevent circulation of drilling fluid whereby the downward pressure of said fluid will move the operating tube and the cross head to 45 actuate the core retaining means, means temporarily holding the cross head against movement until said valve ball has been dropped upon its seat and fluid pressure has been imposed thereon, and means creating a fluid seal between the bore of the housing and the upper end of said operating tube whereby the flow of fluid around the tube will be prevented, a valve member adapted to be dropped 50 through the drill string to rest upon the valve seat and prevent circulation of drilling fluid whereby the downward pressure of said fluid will move the operating tube and the cross head to 55 actuate the core retaining means, means temporarily holding the cross head against movement until said valve ball has been dropped upon its seat and fluid pressure has been imposed thereon, and means creating a fluid seal between the bore of the housing and the upper end of said operating tube whereby the flow of fluid around the tube will be prevented, a valve member adapted to be dropped 60 through the drill string to rest upon the valve seat and prevent circulation of drilling fluid whereby the downward pressure of said fluid will move the operating tube and the cross head to 65 actuate the core retaining means, means temporarily holding the cross head against movement until said valve ball has been dropped upon its seat and fluid pressure has been imposed thereon, and means creating a fluid seal between the bore of the housing and the upper end of said operating tube whereby the flow of fluid around the tube will be prevented, a valve member adapted to be dropped 70 through the drill string to rest upon the valve seat and prevent circulation of drilling fluid whereby the downward pressure of said fluid will move the operating tube and the cross head to 75 actuate the core retaining means.

5. In combination with a core drill, a core catcher, comprising an outer housing having a connection at its lower end for said core drill, and a connection at its upper end for a drill string by which the structure is supported, circulation of fluid from the drill string through the core catcher into the well and through the structure being permitted, and core retaining means within the housing to substantially close the lower end of the core barrel.

CARL FRANCIS BAKER.
